ELECTRIC LIGHTING FIXTURE

Anthony J. Parissi, Cohoes, N. Y.

Application May 12, 1933, Serial No. 670,715

3 Claims. (Cl. 173—348)

My invention particularly relates to an electric lighting fixture designed for use in signaling systems such, for example, as disclosed in my co-pending applications Serial Nos. 701,747 and 51,733 wherein an incandescent lamp is connected through the medium of a three wire circuit for operation, for example, in response to either of two controls.

My invention is primarily designed for simple and efficient incorporation in circuits of the character above referred to, examples of which are herein disclosed merely for purposes of illustration, and has for an object the provision of a combined lamp socket and switch to which may be connected a plurality of wires of an electric circuit. More specifically, a further object of my invention resides in the provision of a fixture comprising a lamp socket and switch which are so electrically connected together and with three terminals for connection to wires of an external circuit that a lamp, which is received in the socket, may be controlled by said switch or by means of any other suitable control which may be connected to the third terminal of the fixture.

With these and other objects in view, my invention includes the novel elements and the combinations and arrangements thereof described below and illustrated in the accompanying drawing in which—

Fig. 1 is a simplified form of signal circuit with which my fixture is adapted for use;

Fig. 2 is a simple form of circuit similar to Fig. 1 and including a plurality of incandescent lamps;

Fig. 3 illustrates a particular form of signaling circuit;

Fig. 4 is an elevation view, partly in section, of a section of a combined lamp socket and switch embodying terminals adapting the same for use in my signaling circuit;

Fig. 5 is an elevation view of the rear of the device illustrated in Fig. 4;

Fig. 6 is an elevation view of a flasher button with the casing removed;

Fig. 7 is a side elevation view of Fig. 6; and

Fig. 8 is an elevation view, partially broken away, illustrating a lamp socket and a switch assembly.

Like reference characters indicate like parts throughout the drawing.

An example of a circuit with my fixture is adapted for use is illustrated in Fig. 1 wherein 1 indicates an incandescent lamp included in a suitable lighting circuit 2. A switch 3, normally adapted to extinguish and light the lamp 1, is

interposed in the circuit with a second switch 4. The switch 4 is wired to control two legs 5 and 6 of the circuit leading to the switch 3, the leg 5 connecting the pole element of switch 3, to one terminal of switch 4 and the leg 6, having included therein an electrically controlled thermostatic switch 7 such, for example, as the well known, so-called flasher button, connecting the other terminal of switch 4 to the terminal of switch 3 which is connected to one side of the lamp 1. The operation of this circuit is as follows:—switch 4, which is adapted to be used by a signaller, is normally in the position indicated in the drawing. The switch 3, used by the operator of the lamp will be, necessarily, either 10 in the off position or in the closed position, in the latter case, of course, the lamp 1 will be illuminated. When it is desired to cause the lamp 1 to emit an intermittent light in order to attract the attention of some person, the signaller 15 throws switch 4 so that the leg 6 is energized through the pole of the switch 4 engaging the terminal 4a thereof. In the event switch 3 is in the closed position and the switch 4 is operated, by the signaller, the leg 5 of the circuit will be 20 opened by switch 4 and the normal supply of current to the lamp 1 will be changed from its path through the leg 5 to leg 6. It is, therefore, evident that the signaller may cause the lamp 1 to 25 flash or flicker independently of the position of the switch 3 and, hence, the switch 3 may be used to light and extinguish the lamp 1, and, independently of the position of said switch, the lamp 30 may be caused to flicker by the signaller through the medium of switch 4.

Fig. 2 illustrates a circuit similar to Fig. 1 wherein a plurality of incandescent lamps 1, 1a and 1b are included in the circuit with a lighting service line 2a which may be energized from any suitable source of power, in most cases, 110 volts 40 being the proper potential imposed thereon. One of the lamps, for example, lamp 1b may be selected as the signaling lamp and in that event it is included in circuit with legs 5a and 6a, the wiring diagram therefor being similar to that 45 of the single lamp illustrated in Fig. 1. Leg 6a has included therein a flasher button 7b and connects one terminal of switch 4b directly to one side of the lamp 1b, whereas leg 5a forms an element of the normal lighting circuit to lamp 1b 50 from the other terminal of switch 4b and includes the usual lamp switch 3a. The operation of this normal lighting circuit and signaling circuit associated therewith is substantially the same as the circuit described above and hence needs no 55

further description nor explanation of the operation thereof.

In Fig. 3, I have illustrated a wiring diagram embodying a particular form of signaling circuit wherein a normal lighting circuit is associated with a telephone circuit. In this case, I have provided means whereby the ringing of the telephone bell may be eliminated and a flashing lamp signal substituted therefor. A three pole socket and plug, indicated generally at 8, is illustrated as a flexible means for connecting any lamp or group of lamps with my signaling device. Obviously the plug and socket is not a necessary part of this circuit for the conductors 9, 10 and 11 leading therefrom to the lamp 1 may be connected directly to the conductors 9a, 10a and 11a respectively in which case the signaling lamp and automatic means for operating the same could be arranged in a single unit. We will assume for the purpose of description that conductors 9, 10 and 11 are connected to the conductors 9a, 10a and 11a respectively and designate them generally as conductors 9, 10 and 11. The normal lighting service lines are indicated at 12, to one of which is connected the common line 9 from one side of the lamp. To the other side of the lamp are connected the two lines 10 and 11, the line 10 forming the other leg of the normal lighting circuit from the lamp through the relay 13 to a conductor 14 and thence to the opposite leg of the service lines 12. The third leg 11 of the lighting circuit is connected to the lamp side of the lamp switch 15 and to one terminal 16 of the relay 13, this leg including a flasher button 7a.

The terminal 17 of the relay 13 is connected to the conductor 14 by means of a conductor 18 having imposed therein an automatic switch element 19 and a manually operable switch 20. The conductor 19 is connected to a terminal 21 of the relay 13 and the terminal 22 thereof is connected to the conductor 14 by the conductor 23. The coil of the relay 13 is connected in series with the two terminals 24 and 25 of a second relay 26, associated with a telephone subscriber's circuit. The two terminals 24 and 25 of the relay 26 are connected to opposite sides of the lighting service lines 12, respectively, through the conductor 28 to the coil of the relay 13, the other end of the coil being connected to one leg of the lighting service lines 12 through the conductors 27 and 9a, whereas conductors 18 and 14 connect terminal 25 to the other leg thereof. The incoming lines of the subscriber's telephone circuit, indicated generally at 29, are connected to a telephone subscriber's set 30 and alarm bell 31. For convenience, I have provided a switch 32 whereby a subscriber may use the bell as an alarm signal or else may substitute therefor a flashing, visual signal. The relay 26 is connected by means of the conductors 33, 34 and the switch 32 in multiple with the subscriber's telephone lines 29.

The operation of the above described circuit is as follows.

Assuming that the switch 32 has been turned to connect the relay 26 in multiple with the subscriber's telephone lines 29, a flow of current in the telephone circuit energizes relay 26, causing the armature 26a thereof to engage the two terminals 24 and 25, thereby closing a circuit therebetween. Normally the armature 13a of the relay 13 is in the position illustrated in Fig. 3, the coil thereof being unenergized and the normal lighting circuit to the incandescent lamp 1 being established thereby. The conductors 9 and 9a form one leg of the normal lighting circuit to said

lamp, the other leg comprising the conductor 10 and switch 15 included therein, the conductor 10a, terminals 21 and 22, electrically connected together by means of the armature 13a, conductors 23 and 14 to the other side of the service lines 12. An energization of relay 26 effects an energization of relay 13 causing the circuit otherwise established thereby to be opened between the terminals 21 and 22 thereof and closing a circuit between terminals 16 and 17. Therefore, the normal lighting circuit to the incandescent lamp 1 is opened and a new circuit is made which functions as a substitute for the normal one, the leg of the normal circuit including the switch 15 being rendered inoperative. Relay 13 is preferably of the locking type to maintain the substitute circuit irrespective of further operation of the telephone system. Furthermore, a flasher button may be incorporated in the substitute circuit to provide intermittent illumination of the lamp and thereby provide a visual signal. From an inspection of the foregoing circuit, it is evident that intermittent illumination or flashing of the lamp will take place irrespective of whether the lamp was lighted or extinguished at the time of operation of the signal circuit.

The manually operable switch 20 is provided to permit a person responding to the signal to open the substitute circuit and restore the normal lighting circuit and the automatic switch 19, a timing switch of any desired type, effects the same result when the signal is unanswered.

In Figs. 4 and 5, I have illustrated a portion of a lighting fixture embodying my invention which is particularly adapted for use with signaling circuits of the foregoing character. The switch casing 36 is of the usual type incorporated in an electric lighting fixture (see Fig. 8) and comprises the usual terminal 37 to which one side of the lighting circuit is connected. A second terminal 38 is provided having the usual spring contact 39 adapted to bear against the base of an incandescent bulb when the same is screwed within the lamp socket. The terminal 37 is electrically connected to the terminal 38 at the will of an operator by means of a segmental, metallic wheel, not illustrated but of well known construction, the segments thereof being adapted to bear against the plate 37a of the terminal 37 and plate 38a of the terminal 38 when the switch is in the closed position. When the switch is again operated these segments will pass beyond and away from engagement with the plates 37a and 38a and lie in the recesses 40 and 41 cast in the shell 36 of the switch element. The design of this type of switch is well understood in the art and needs no further description thereof in order to explain the function of the added terminal 42 which adapts my fixture for use with, for example, three wire circuits. The terminal 42 is located at any convenient position on the outer portion of the switch casing and extends therethrough to the interior thereof and is electrically connected to the portion 38b of the terminal 38. The terminal 42 is adapted to form a means for connecting the socket and lamp associated therewith directly across two wires of a circuit and at the same time permit a third wire to be connected to the terminal 37 whereby the switch element may be used to regulate the operation of the lamp when the circuit is completed through the conductor attached to the terminal 37.

To the switch casing 36 is secured a lamp socket 48 of the usual type within which an incandescent lamp is receivable. The socket is pro-

vided with diametrically opposed, depending lips 48, one of which is shown in Fig. 5, adapted to embrace opposite sides of the switch casing with the openings in said lips in registry with an opening extending transversely through the switch casing. A bolt 50 passing through the openings in the opposed lips and the transverse opening of the casing serves to maintain the switch and socket in assembled relation. The bolt 50 may be firmly retained in position, for example, by a nut or the threaded end thereof may be engaged by threads formed in the opening in one of the lips. One conductor 51, diagrammatically illustrated in Fig. 5, is suitably secured to bolt 50, which forms one terminal of my fixture, and conductors 52 and 53 are connected respectively to the terminals 42 and 37 thereof.

Obviously, terminals 42 and 50 serve to connect the lamp socket directly across the two conductors 51 and 52 of a three wire circuit and terminals 37 and 50 serve to connect the socket and switch in series across the conductors 52 and 53 of the circuit.

In Figs. 6 and 7 I have illustrated a type of 25 flasher button in order to aid in an explanation of the operation thereof. The flasher button indicated generally at 43 comprises an armature 44 having a coil 45 wound thereon and a contact button 46, adapted to engage a contact 47 when 30 the armature 44 bends toward the right as viewed in Fig. 7 as a result of the energization of coil 45. The coil 45 is adapted for connection in series in an electric circuit and intermittent shunting thereof is effected by engagements of contacts 35 46 and 47 whereby an intermittent flow of current is effected through the circuit.

While in the foregoing I have described my invention in connection with exemplary uses thereof, it is to be understood that my fixture may be 40 employed with any type of circuit and is not limited to those of the character, termed signaling circuits, herein disclosed. Hence, while I have described my invention in its preferred embodiments, it is to be understood that the words 45 which I have used are words of description rather

than of limitation, and that changes within the purview of the appended claims may be made without departing from the true scope and spirit of my invention in its broader aspects.

What I claim is:—

1. An electric lighting fixture comprising a lamp socket having two contacts adapted to engage the contacts of an incandescent lamp received therein, a switch, and three terminals electrically insulated from each other, two of said terminals being electrically connected directly to respective lamp socket contacts whereby said socket may be connected directly across two legs of an electric lighting circuit, and the third terminal being electrically connectible through said switch to one of said socket contacts; said terminals being arranged to permit the connection of said fixture in an external electric circuit.

2. An electric lighting fixture comprising an incandescent lamp socket having two contacts 20 adapted to engage the contacts of an incandescent lamp, a switch, and three separately insulated terminals disposed exteriorly of said switch and socket for connection to external electrical conductors, two of said terminals being 25 connected to form a circuit including said socket and switch in series therebetween and the third terminal being electrically connected to said circuit at a point intermediate said switch and lamp socket.

3. A combined switch and socket for an incandescent lamp, said socket having two contacts adapted to engage the contacts of an incandescent lamp received therein and said switch having a casing provided with three separately insulated 35 terminals disposed exteriorly thereof, two of said terminals being directly connected respectively to the two socket contacts and the third terminal being electrically connectible through said switch to one of said socket contacts; said terminals being 40 adapted to permit the connection to said switch and socket of three wires of an electric circuit.

ANTHONY J. PARISSI. 45
